(57) **CLAIM**

The ornamental design for a computer screen display or a portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a computer screen display or portion thereof with graphical user interface showing the new design.

The outermost broken line illustrates the display screen, and the broken line showing of text, square-shaped boxes, and rectangular boxes within the outermost broken line illustrates portions of the graphical user interface. None of the broken lines form part of the claimed design.
